UNITED STATES PATENT OFFICE.

WILLIAM W. BROWN, OF SCHENECTADY, NEW YORK, ASSIGNOR TO GENERAL ELECTRIC COMPANY, A CORPORATION OF NEW YORK.

ELECTROMAGNETIC SWITCH.

Application filed March 10, 1921. Serial No. 451,091.

To all whom it may concern:

Be it known that I, WILLIAM W. BROWN, a citizen of the United States, residing at Schenectady, county of Schenectady, State of New York, have invented certain new and useful Improvements in Electromagnetic Switches, of which the following is a specification.

My invention relates to improvements in electromagnetic switches. One of the objects of the invention is the provision of an improved electromagnetic switch in which the friction of the moving parts is reduced to a minimum. Another object is the provision of an improved arrangement whereby the switch contacts shall have the desirable cushioning and wiping actions. A further object is the provision of an improved arrangement whereby the switch will be capable of repeated operation at a high speed.

In carrying my invention into effect in one form, I provide a pair of cooperating switch contacts, one of which is movable and is biased to one position. An electromagnet is provided for operating the movable contact to a second position, and the electromagnet is provided with a plunger which is supported at both of its ends within the winding of the electromagnet and is operatively connected at both of its ends with the movable contact. The plunger of the operating electromagnet is suspended within the winding of the electromagnet so as to be freely movable without friction. The movable switch contact member is preferably resilient and is also resiliently mounted so that the contacts of the switch are given a wiping action in closing and the contacts have also a cushioning effect which is desirable for minimizing the wear on the contacts.

For a better understanding of the invention, reference is had to the accompanying drawing which illustrates an embodiment of the invention for purposes of illustration and in which Fig. 1 shows a side view of one form of my improved electromagnetic switch, and Fig. 2 is a front view of the switch.

Referring to the drawing, the switch is provided with the stationary contact 10 which is held in the supporting member 11. Cooperating with this stationary contact is a movable contact 12 which is connected to a resilient contact member 13 yieldingly con-

nected to the supporting base 14 by means of the thin metallic strip 15. The operating electromagnet 16 of the switch is provided with a plunger 17 which is supported at each of its ends in proper position within the winding of the electromagnet. The left-hand end of the plunger is provided with a member 18 which cooperates with the surface of a bearing support 19 which is secured to the resilient contact member 13 to form a knife-edge type of pivotal connection. The right-hand end of the support is provided with an end 20 which cooperates with the bearing surface of a support 21 secured to the resiliently mounted supporting rod 22 to form a similar knife-edge pivotal support. The knife edge pivotal supports for the plunger permit of minor relative movements between the plunger and the contact member. However, the plunger is supported in such a manner that it has practically only an axial movement of the magnet winding, so that rubbing of the plunger on the interior surface of the spool on which the magnet winding is mounted is thus prevented. The lower end of the rod 22 is yieldingly connected with the supporting base 14 by means of the thin metallic strip 23 and the upper end thereof is connected with the contact member 13 by means of the spring 24. A compression spring 25, which is disposed within the supporting strap 26 so as to press on the plunger in the line of movement of the plunger, is provided for biasing the plunger 17 to its right-hand position. The strain of the spring 25 can be adjusted by means of the adjusting screw 27 and the gap between the plunger 17 and the core of the operating electromagnet can be adjusted by means of the adjusting screw 28.

A conducting chute 29 is provided for directing a blast of air across the contacts 10 and 12 in order to cool these contacts and thereby permit large currents to be carried, and also for the purpose of extinguishing the arcs formed between the contacts when they separate.

As thus constructed and arranged, and with the parts in the various positions shown in the drawings, the operation of my invention is as follows: When the winding of the electromagnet 16 is energized, the plunger 17 is drawn quickly to the left within the winding of the electromagnet, and in so doing carries with it the

contact member 13 so as to cause the movable contact 12 to make engagement with the stationary contact 10. Through the medium of the spring 24, the supporting rod 22 5 will follow the movement of the contact member 13 and maintain the right-hand support for the armature 17. The spring 26 will be put under compression tending to move the plunger of the electromagnet 10 to its right-hand position, but as long as the electromagnet is energized, the plunger will be maintained in its left-hand position and the switch contacts will be closed. When the electromagnet is deenergized, the 15 spring 26 will cause the contact 12 to return to the open position, and the plunger 17 to be moved to its right-hand position, that shown in the drawing.

In case it is desired to adjust the switch 20 to operate at a different value of current in the magnet winding, the adjusting screw 28 will be turned until the plunger 17 is at the proper position. In case it is desired that the movable contact 12 shall have 25 a greater biasing effect toward the open position, the adjusting screw 27 will be turned until the desired biasing effect is obtained.

The stationary contact 10 may readily be 30 adjusted with reference to the movable contact 12 by loosening the bolts 30 and adjusting the contact to the desired position.

Although not necessarily limited thereto, my invention has a particular application 35 in switches which are required to be repeatedly and quickly operated as, for instance, switches for controlling an electric circuit for sending wireless signals. A switch constructed in accordance with my invention will have a very small friction effect, so that the speed of operation can be very great.

Because of the resilient mounting for the 40 switch member 13, the contacts will be given a wiping action in closing and there will be a cushioning effect when the contacts make engagement.

In accordance with the provisions of the 45 patent statutes, I have described the principle of operation of my invention, together with the apparatus which I now consider to represent the best embodiment thereof, but I desire to have it understood that the apparatus shown is only illustrative and that the invention can be carried out by other means.

What I claim as new and desire to secure by Letters Patent of the United States, is:—

1. An electromagnetic switch comprising 60 a switch contact biased to one position, an electromagnet having a plunger for operating the contact to a second position, supports for the ends of the said plunger, and connections between the said supports and the said switch contact for supporting the said

plunger at both of its ends and operatively connecting both ends of the plunger with the contact.

2. An electromagnetic switch comprising a switch contact biased to one position, an electromagnet having a plunger for operating the contact to a second position, a resilient support for supporting one end of the said plunger, and means for supporting the other end of the plunger and operatively connecting both ends of the plunger with the said contact. 70 75

3. An electromagnetic switch comprising a resiliently mounted contact member movable to and from an operative position, a resiliently mounted support resiliently connected to the contact member, and an operating electromagnet having a plunger supported between the contact member and the 80 said support. 85

4. An electromagnetic switch comprising a contact member movable to and from an operative position, an electromagnet having a plunger for operating the contact member, a movable support, and a spring connecting the support and the contact member for holding the said plunger between the member and the support. 90

5. An electromagnetic switch comprising a contact member movable to and from an operative position, an operating electromagnet having a plunger for operating the contact member, a support mounted on the contact member for one end of the plunger, and a support for the other end of the plunger 100 connected to and movable with the contact member. 105

6. An electromagnetic switch comprising a contact member movable to and from an operative position, an operating electromagnet having a plunger, means for biasing the contact member and plunger to one position, a support for one end of the plunger, means connecting the said support with the contact member for holding the said plunger between the contact member and the support and operatively connecting the plunger with the contact member. 110

7. An electromagnetic switch comprising a contact member movable to and from an operative position, an electromagnet having a plunger for operating the contact member, a movable support, a spring connecting the support and the contact member for holding the plunger between the contact member and the support, and pivotal connections between the ends of the plunger and the contact member and the said support for supporting the plunger and operatively connecting the same with the contact member. 115 120 125

8. An electromagnetic switch comprising a resiliently mounted contact member movable to and from an operative position, an electromagnet having a plunger for operating the member, a resiliently mounted sup-

port, a spring connecting the member and the support, pivotal connections between the ends of the plunger and the contact member and support for supporting the plunger and operatively connecting the same with the contact member, and means for adjusting the positions of the contact member and the plunger.

9. An electromagnetic switch comprising
10 a resiliently mounted contact member movable to and from an operative position, an electromagnet having a plunger for operating the contact, a resiliently mounted sup-

port, a spring connecting the support and the contact member, knife-edge pivotal connections between the ends of the plunger and the contact member and support for supporting the plunger and operatively connecting the same with the contact member, means for biasing the contact member to one position, and means for adjusting the position of the plunger.

In witness whereof, I have hereunto set my hand this 8th day of March, 1921.

WILLIAM W. BROWN.
